(57) **CLAIM**

The ornamental design for a simulated cabin chair, as shown and described.

DESCRIPTION

FIG. 1 is a front, left and top perspective view of a simulated cabin chair showing our new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view showing the area “9” in FIG. 1;

FIG. 10 is a partially enlarged view showing the area “10” in FIG. 1;

FIG. 11 is a partially enlarged view showing the area “11” in FIG. 2;

FIG. 12 is a partially enlarged view showing the area “12” in FIG. 2; and,

FIG. 13 is a partially enlarged view showing the area “13” in FIG. 2.

The even broken lines depict portions of the simulated cabin chair that form no part of the claimed design.

The dot-dash broken lines indicating an enlargement portion of the design form no part of the claimed design.

1 Claim, 13 Drawing Sheets
